UNITED STATES PATENT OFFICE.

FREDERICK K. MAERZ, OF CLEVELAND, OHIO, ASSIGNOR TO THE SCOTT-ULLMAN COMPANY, OF CLEVELAND, OHIO, A CORPORATION OF OHIO.

DESIGN FOR A LIGHTING-FIXTURE.

50,998.

Specification for Design.

Patented July 3, 1917.

Application filed May 11, 1917. Serial No. 168,047. Term of patent $3\frac{1}{2}$ years.

To all whom it may concern:

Be it known that I, FREDERICK K. MAERZ, a citizen of the United States, residing at Cleveland, in the county of Cuyahoga and State of Ohio, have invented a new, original, and ornamental Design for Lighting-Fixtures, of which the following is a specification, reference being had to the accompanying drawing, forming part hereof, wherein the figure is an elevation of a lighting fixture exhibiting my new design.

I claim:—

The ornamental design for a lighting fixture, as shown.

FREDERICK K. MAERZ.

Witnesses:

H. B. MCGILL,
K. N. SOMMERS.
